CLAIM

The ornamental design for a jewelry, charm or similar article, substantially as shown and described.

DESCRIPTION

FIG. 1 is a front elevational view of a jewelry, charm or similar article showing my new design;

FIG. 2 is a left side elevational view thereof;

FIG. 3 is a right side elevational view thereof;

FIG. 4 is a front elevational view of a jewelry, charm or similar article showing a modified form of my new design; and

FIG. 5 is a front elevational view of a jewelry, charm or similar article showing another modified form of my new design.
